CLAIM

The ornamental design for a pest trap, as shown and described.

DESCRIPTION

FIG. 1 is a rear perspective of the pest trap showing the design in an environment of use.

FIG. 2 is an exploded rear perspective view thereof; FIG. 3 is a front elevational view thereof, with a flap door in a closed position;

FIG. 4 is a front elevational view of FIG. 3;

FIG. 5 is a right-side elevational view of FIG. 3, the left-side elevational view being a mirror image thereof;

FIG. 6 is a top plan view of FIG. 3;

FIG. 7 is a bottom plan view of FIG. 3;

FIG. 8 is a bottom perspective view thereof, illustrated with the flap door in an open position;

FIG. 9 is an exploded bottom perspective view of FIG. 8;

FIG. 10 is a front elevational view of FIG. 8; and,

FIG. 11 is a cross-sectional view of FIG. 3, taken along line 11-11 of FIG. 3.

The broken lines of FIG. 1 depicting an environmental bottle form no part for the claimed design.
